DOOR LOCKING DEVICE FOR AUTOMOBILES AND THE LIKE

Edward D. Dall, Waukegan, Ill., assignor to Walter F. Wright, Shaker Heights, Ohio

Application February 4, 1933, Serial No. 655,180
Renewed June 8, 1937

30 Claims. (Cl. 70—264)

My present invention is a door-locking and window-closing device for use with automobiles and elsewhere wherever useful.

One object of the invention is to lock all of the doors automatically from the locking of a master-door.

Another object is to accomplish said locking either from the outside of the car or from within. If from within, another object is to permit the occupant to open any door, leave the car and shut the door without locking the party out of the car by so doing.

For a modification, another object is to lock a plurality of the doors from a suitably located single control, which does not simultaneously lock the master-door, the bolt means of the latter being dogged or locked independently from the outside of the car.

Another object is to close the windows in the doors automatically from the locking of the doors.

Another object is to prevent the closed windows of the door-locked car from being forcibly opened from the outside.

Another object is to permit, in connection with the foregoing, the individual opening and closing of the windows in the regular way by hand from within the car after the master and other doors have been unlocked.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure, a preferred embodiment of my invention, it being expressly understood, however, that various changes may be made in practice within the scope of the claims without digressing from my inventive idea.

In the drawings:

Fig. 1 is a fragmentary elevation of portions of the doors, windows and center post of an automobile on the master-door side thereof, some portions being broken away to reveal underlying structure and other portions being shown in section.

Fig. 2 is a view similar to Fig. 1 of the doors, etc. on the opposite side of the car.

Fig. 3 is an enlarged view of the bolt means retracting means and the dogging means of the master-door and adjacent parts, shown unlocked.

Fig. 4 is the same when locked.

Fig. 5 is a vertical sectional view on the line 5—5 in Fig. 4.

Fig. 6 is an enlarged view of the bolt means retracting means and dogging means of one of the non-master doors.

Fig. 7 is the same as Fig. 6 except that it shows the parts in a different position.

Fig. 8 is a perspective view of a portion of Fig. 6.

Fig. 9 is a horizontal sectional view on an enlarged scale through a portion of the devices in Fig. 1, or on the line 9—9 in Fig. 10.

Fig. 10 is an enlarged broken away view of a portion of the center post in Fig. 1 and of the contained and related parts.

Fig. 11 is a horizontal section on the line 11—11 in Fig. 12.

Fig. 12 is an enlarged broken away view of a portion of the center post in Fig. 2 and of the contained and related parts.

Figs. 13 and 14 are perspective views of the broken away center posts respectively and of the contained and related parts.

Fig. 15 is an enlarged view of one of the window operating mechanisms shown in Figs. 1 and 2.

Fig. 16 is a combined vertical section and elevation on the line 16—16 in Fig. 15.

Fig. 17 is a perspective view of parts from Fig. 15 or 16 in spaced apart order.

Fig. 18 is a cross sectional view on the line 18—18 in Fig. 16; and

Fig. 19 is a side elevation of a master-door handle and combined key-operated means usable in connection with the devices of this invention.

Fig. 20 shows a modification substitutable for the master-door dogging means and slide-operating means in Fig. 1;

Fig. 21 shows another modification similarly substitutable in Fig. 1; and

Fig. 22 shows still another modification substitutable in Fig. 1 for the dogging means and slide-operating means.

Referring now to the drawings:

A and B are the doors on the right side of the automobile, A being the master door, so called because by locking A, all the other doors are automatically locked, a and b are the windows in said doors respectively. E is the center post of the automobile body on the master door side of the car between the free edges of said doors A and B, which are supposed to be hinged as usual at their edges furthest away from the center post.

In the same way C and D are the doors on the left or the driver's side of the car, c and d being the windows thereof respectively; and F is the

center post between the free edges of said doors.

Describing first the locking means for the master door A, see particularly Figs. 1 and 3, 4 and 5. 10 is a plate on the door for supporting the parts. 12 is the usual bolt pressed by the spring 14 into projecting position to enter the usual socket in the post E. 16 is the usual suitably supported shaft of the handle 18 shown in detail in Fig. 19. 20 is the usual vertically slidable dog operative in a transverse slot in the handle shaft, adapted to be shifted by a key-controlled means carried by the outside handle and shaft, between the "down" position of said dog in Fig. 3 and its "up" position in Fig. 4. Sufficient details of this are shown in Fig. 19 disclosing outside door handle 18, its shaft 16, key 22, barrel 24 rotatable by said key, rotatable shaft 26 which is a continuation of said barrel and has at its free end an eccentric pin 28 received in a groove 30 in the dog, which latter is thereby operable as stated between the aforesaid two positions (Figs. 3 and 4) by the rotation of the key-controlled barrel.

32 is a so-called roll-back secured to the handle shaft and having an upper projection 34 in front of a lug 36 on the bolt, for retracting the bolt by rotating the outside handle and shaft 16. 38 is a slide operatively supported for horizontal reciprocation below the roll-back. This slide has an upwardly extending projection 40. The roll-back has a lateral projection 42 which is clear of said projection 40 on the slide when positioned as in Fig. 3, but is in line with it when the slide is positioned as in Fig. 4. A tilting cam 44 is pivoted to the plate at 46 with its nose engaged by said lateral projection 42 on the roll-back and with its lower front corner at the end of the slide 38. The result is that turning the handle, its shaft 16 and the roll-back 32 in anticlockwise direction as in Fig. 4, operates the cam 44 to project the slide 38 to its maximum extent beyond the free edge of the door as compared with its normal position in Fig. 3. Spring means 48 (Fig. 1) pulls on the wire 50 attached to the forked inner end of the slide 38. This spring means duplicated on all the doors is later described in detail in connection with Figs. 1, etc. and Fig. 17; and said spring means on the master-door constantly tends to retract the slide 38 into its inner position as in Fig. 3. The projection 40 of the slide being under the lateral projection 42 of the roll-back, the handle and handle shaft 16 cannot be turned clockwise sufficiently to retract the bolt 12.

52 is a latch pivoted to the plate at 54 and is pressed by the spring 56 upwardly under the slide. 58 is a projection at the free end of the latch receivable into a notch on the under side of the slide. Finally, 60 is an upward extension on the free end of the latch at the side of the slide in line with and engageable by the lower end of the previously described key operated dog 20 in the handle shaft. When this dog is in its position Fig. 4, it will be noted that the latch 52 is in locking engagement with the slide 38 preventing its retraction by the referred to spring means 48 (Fig. 1) pulling on the rod 50.

Summarizing the operation of the master-door lock, Fig. 3 shows the unlocked condition and Fig. 4 the locked condition. Locking the master-door, in other words, dogging its bolt retracting means to prevent the retraction of the bolt by the outside handle, is accomplished as follows: The key 22 (Fig. 19) being turned in the master-door handle 75 into locked position shifts the dog 20 into upper

position (Fig. 4) thereby rendering the latch 52 operative. The door handle 18 (Fig. 19) and shaft 16 (Fig. 3) are then rotated anticlockwise from the position in Fig. 3 to the position in Fig. 4, and through the roll back 32 and cam 44 force the slide 38 to the left against the pull of the spring means on the rod 50 into abutting position under the roll back as in Fig. 4, wherein it is latched by the latch 52. The bolt retracting means is now dogged and the master-door handle 10 cannot be turned to retract the bolt 12. Moreover the slide 38 cannot be tampered with and forced back because it is latched. Thus the bolt retracting means has been dogged by the counter clockwise turning of the door handle and also 15 by the key means, the latter being necessary to latch and hold the dogging means in its operating position.

To unlock the master-door:—the key is inserted in the door handle and turned to unlock- 20 position (Fig. 3). This lowers the dog 20 as in Fig. 3, releases the latch 52 from the slide 38 which is then automatically retracted by the spring means pulling on the rod 50 and thereby un-dogs the roll back 32, permitting the handle 25 and shaft 16 to be turned clockwise to retract the bolt and open the door.

Referring now to the bolt and the retractor dogging means for the non-master doors B, C, and D, said means is or may be identical for 30 said doors so that the following description of one suffices for all. Referring to Fig. 1 or 2 and the enlarged views 6 and 7, each bolt-means and retractor dogging-means for these non-master-doors comprises:—a plate 62 for operatively sup- 35 porting the parts; a bolt 64; a spring 66 for projecting the bolt; a shaft 68, Fig. 6 for an outside door handle; a roll back 70 with upward projection 72 to engage a lug 74 on the bolt for retracting the bolt by anti-clockwise rotation of 40 the handle against the pressure of the above spring 66; a tiltable dog 76 pivoted at 78 to the plate having an upper end engageable at times by a pin 80 on the bolt as will be hereinafter explained; said dog further having a shoulder 82 45 receivable by the tilting of the dog into dotted line position Fig. 6 under a lateral projection 84 of the roll back thereby preventing retraction of the bolt by the outside handle. A slide 86 is supported for endwise reciprocation below the 50 bolt with one end projectable beyond the free edge of the door. It has a notch 88 (Fig. 8) receiving the lower end of the tiltable dog, whereby reciprocation of said slide and its associated spring clip operates the dog into and out of dogging position. The spring clip, designated as a whole by 90, has a part in this as an adjunct of the slide 86 but its construction and operation can be more opportunely described later on. The slide in its fully projected position shown in Fig. 6 tilts the dog into the full line non-dogging position shown. Reversely when in its in- 60 most position, the clip ordinarily engages and tilts the dog into the dotted position Fig. 6 wherein its shoulder 82 dogs the bolt retracting means by preventing rotation of the handle to retract the bolt. The slide is spring pressed into its outermost projecting position by the upper end of a lever 92 pivoted at 94 to the plate with 70 its lower end pulled yieldingly to the left (Fig. 6) by spring means 48 (Figs. 1 and 2 etc. and Fig. 15) described later, acting on wire 50 (Fig. 6). Thus when the bolt retracting means of the non-master doors are dogged so that said doors 75

cannot be opened by their outside handles, the slides 86 of said non-master-doors are "in" viz. are in their least projecting position. As distinguished from this, the slide 38 of the master-door at such time (Fig. 4) is in its maximum projecting position as already described.

The center posts E and F of the automobile body are formed with horizontal slots 96 (Figs. 10, etc.) which receive and pass freely the projecting ends of the slides 38 and 86 so that they do not interfere with the opening and closing of the doors.

Means now to be described located within the post E delivers the outward thrust of the master-door slide 38 (when same is projected to dog the bolt means of that door) directly across to the slide 86 of the door B to press same inwardly and thereby automatically dog as above explained the bolt means of said door B. This motion conveying means within the post E comprises hinged tablets 98 (best shown in the enlarged detail views Figs. 9-14) supported within the post adjacent the aforesaid slots 96. The tablets are hinged at their outer ends on vertical pins 21 supported on stationary brackets 23 so that the free ends of the tablets can swing towards and away from the slotted sides of the post. A thrust member, in this case a rigid strip 25 with right-angle ends is suitably supported for horizontal reciprocation in contact at the ends with the tablets whereby the thrust of the master-door slide 38 (Fig. 13) against its tablet is directly conveyed by the strip 25 to the other tablet and to the slide 86 of the other door B; and vice versa an outward thrust of the latter slide due to its spring means 48 (Fig. 1) is conveyed to the master-door slide.

Referring to the motion conveying means for operating the slides of the doors C and D on the other side of the car from the master-door, this means comprises the following:—27 is a bell crank lever pivoted at 29 within the post E (well shown in Fig. 10 or 13) with one arm at the tablet 98 at the master-door slide 38. Its other arm has a pin 31 projecting through an arcuate slot 33 in the back wall of said post. A Bowden-wire 35 operatively connects this pin to a tilting cam-lever 37 pivotally supported at 39 within the other post F (well shown in Fig. 12 or 14). The cam shaped ends of this lever are in operative engagement with the hinged tablets 98, which latter are in all respects similar to the previously described tablets having the same designating numeral in post E. The combination is such that the outward thrust of the master-door slide 38 operates the bell crank lever 27 to pull on the movable element of the Bowden-wire 35 (which latter it will be understood is supposed to extend across the car either at the floor, or under the roof, or at or in the back of the front seats) which in turn tilts the cam lever 37 in the post F to swing the tablets therein simultaneously away from each other, that is to say, outwardly against the slides 86 with the result that said slides are pressed into their innermost position thereby dogging the bolt means of the doors C and D as already explained.

Reviewing now the operation as a whole of the devices so far described:—the master-door A is locked as already explained in detail by using the key 22 (Fig. 19) and operating the master-door handle 18 and shaft 16 (Figs. 1, 3, and 4) counterclockwise. Incidentally this projects the slide 38 of the master-door which through the

described motion transferring devices in the center posts E and F including the connecting Bowden-wire 35, automatically presses inwardly the slides 86 of all the other doors, thereby dogging their bolt retracting means and preventing the opening of said doors by their outside handles as heretofore explained. Vice versa, as soon as the key is turned to unlock the master-door, its spring means 48 (Fig. 1) as explained instantly retracts its slide 38 and undogs its bolt retracting means so that its handle and handle-shaft 16 can be turned clockwise in Fig. 3 to unbolt said master-door. The retraction of the master-door slide 38 also automatically undogs the bolt means of all the other doors because then said master-door slide no longer prevents the outward movement of the slides 86 of the other doors, impelled as they are by their respective spring means 48 (Figs. 1 and 2), so that said slides now spring outwardly and thereby tilt the dogs 76 out of dogging position and release the bolt retracting means 70 of all these doors for operation by their outside handles on the shafts 68. When slides 86 on the two left side doors move outwardly, lever 31 is returned to the position of Figs. 2 and 12 by tablets 98 acting against the cam ends of lever 37.

I also provide means whereby the doors are simultaneously lockable and unlockable from within the door as follows:—39 (Figs. 1 and 3, etc.) is a slidable member supported and guided for horizontal reciprocation on pins 41 projecting from the master-door plate into horizontal slots in the slide. The usual hand lever 43 on the inside of the master-door is operatively connected by a link 45 with the slidable member whose front end is positioned to engage and push outwardly the slide 38 of the dogging mechanism of the master-door lock, when said inside handle is suitably operated. It will be seen that this not only dogs and locks the master-door from being opened from the outside, but will likewise automatically dog and lock the other doors due to the heretofore described action of the motion conveying devices in the posts and the Bowden-wire and the resultant in-pressing of the slides 86 of said other doors.

47 is a latch (Figs. 3 and 4) centrally pivoted at 49 to a stationary support. The latch at one end overlies the key operated dog 20. A spring 51 yieldingly maintains the latch in contact with said dog. The opposite end of the latch is beveled and faces a pin 53 on the aforesaid slidable member 39. When said member is operated by the inside handle 43 as aforesaid to dog the bolts of all the doors, said pin 53 on said member pressing against the beveled end of said latch 47, tilts it downwardly until the pin is received into a notch 55 in the upper end of the latch. This occurs when the slidable member 39 has been moved far enough to dog the bolt means of the doors. Tampering with the master-door slide 38 to unlock the doors from the outside is prevented by the described latch. On the other hand, it does not interfere with the unlocking of all the doors simultaneously from within the car by operating the inside handle 43 of the master-door to retract the slidable member 39 because the pin 53 of the latter merely rides out of the notch 55 by camming the notched end of the latch downwardly. Also the latch 47 can be released from the member 39 from the outside of the car by turning the key in the master-door lock to elevate the dog 20 as in Fig. 4, which it will be seen from

that figure tilts the aforesaid latch 47 so as to release the slideable member 39 whereupon the spring-tensioned wire 50 operates the master-door slide 38 to undog the master-door and simultaneously permits the operation of the slides 86 of the other doors to undog their bolt retractors 70.

Moreover, each of the other doors B, C, and D is provided with an inside handle lever 57 (Figs. 10 1 and 2) linked to its bolt 64 which is always operable by an occupant of the car to retract the bolt of the particular door to permit opening the door from within the car, despite the fact that all of the doors may have been previously locked against being opened from the outside, whether by the key and outside handle means of the master-door, or by the inside handle 43 of said door. The advantage will be appreciated of being able to lock one's self in a parked 15 car without being disturbed by anyone opening the doors from the outside, or stealing articles from the car.

In case an occupant of the car opens one of the locked non-master-doors B, C, or D by operating its inside handle 57 and then steps out of the car and shuts the door, this without further mechanism would result in locking said person out of the car, because on shutting the door, its slide 86 would ride against its tablet 98 and would be forced back again into its innermost position wherein it tilts its dog 76 into dogging position as shown by the dotted lines in Fig. 6. To prevent this contingency is the object of providing the heretofore referred to so-called spring clip having the general designation 90 on each of the slides 86. This clip is well shown in Fig. 8 and consists of a piece of spring wire having a U-shaped end 90a threaded through parallel holes in the slide for attaching the wire clip thereto. Further, said clip has a free end 90b which generally parallels the slide longitudinally but is bent at its extremity to form a toe-portion 90c which is located nearer the axis of the slide and which is connected by a slightly inclined portion 90d with the main part 90b of the clip. The interrelation of the parts is such that they operate as follows:—Assuming that the non-master-door, which has been automatically locked against opening from the outside, is the one indicated in Fig. 6, and that therefore, its tilting dog 76 is in the dotted position against the pin 80 of the extended door bolt; should now the assumed contingency occur of the occupant retracting the bolt by its inside handle 57 (Fig. 1 or 2), said pin 80 (Fig. 6) on said bolt would tilt the dog 76 out of dogging position and would cause the lower end of the dog to ride partly past and under the toe-portion 90c (Fig. 8) of the spring clip on the slide and would cause same to be frictionally held thereby as shown in Fig. 7. The result is that even if the person alights from the car and unthinkingly shuts the door, the dog will be held by the spring clip and will be prevented from returning into the dotted line dogging-position shown in Fig. 6, and therefore the door can be re-opened from the outside. When a door re-opened from the outside. When a door is away from its associated tablet 98 and the pull of spring 48 on 50 will cause slide 86 to move outwardly. This will carry the end 90c of the clip off the end of dog 76. However, when the door is again closed bolt 64 hits the striker on the door post and slide 86 hits the tablet 98 (which is extended toward the free edge of the door). Both

these parts are thus moved to the position of Fig. 7, again placing the clip end 90c on the dog 76.

On the other hand, the clip 90 will be automatically released from the aforesaid position shown in Fig. 7 and will be restored to its normal working position as soon as the spring pressed slide 86 is released, as by unlocking the master-door, because then said slide will carry the clip to the right in Fig. 7 off the dog 76 which at such time is prevented from swinging about its pivot 10 18 by the stop pin 17 supported by the plate 62.

I will now describe the means whereby any and all windows of the doors if open will be automatically closed by the locking of the master-door, whether this be done from the outside of 15 the car or from within.

In the first place, each door is shown equipped with the usual vertically slideable glass window a, b, c or d as a closure for the usual opening in the upper part of the doors. Also a well known 20 form of means for raising and lowering the windows individually is provided on each door but with important modifications for the purposes of this invention. This well known means comprises the following:—59 is a gear toothed sector 25 having a shaft 61 supported in suitable bearings not shown in the stationary plate 63 or other suitable support or housing on the door as indicated in Figs. 1, 2, etc. A radial arm 65 rigid with the sector has a pin 67 (which may be surrounded 30 by a rotatable sleeve to reduce friction) located within a horizontal slot 69 formed in the frame at the bottom of the window. 71 is a pinion on a short slotted shaft 73 (Figs. 16 and 17) operatively supported for rotation by stationary plate 35 63 in a suitable bearing as indicated in Fig. 18. A handle 75 on handle-shaft 77 is indirectly connected with the aforesaid pinion shaft 73 and is exposed on the inside of the car for manually turning the pinion 71 and the section 59 in either 40 direction in order to raise or lower the window as desired by the action of the aforesaid sector arm 65 on the lower edge of the window. A coiled spring 79 has its inner end secured to the shaft 61 Fig. 15 of the sector and is coiled under tension about said shaft with its outer end 79a secured to the stationary plate or housing 63 so that the tendency of said spring to unwind tends to rotate the sector and its arm in opposition to the pinion to counterbalance the weight of the 50 window. The foregoing is the function and strength given to this spring 79 in the ordinary device but for the purpose of this invention I make it much stronger so that each spring will operate to close its window whenever released 55 and permitted to do so, as will later appear.

The operative connecting means between the handle-and-pinion-shafts 71 and 73 comprise the following:—the free end of the handle shaft consists of a sleeve or cup 81 formed with a slot 81a through its wall. 83 is an annularly channeled washer surrounding the pinion shaft at the opposite face of the stationary support 63 from the pinion 71 as shown in Fig. 16. When the parts thus far described are assembled as shown in Fig. 16, it will be seen that the handle-shaft-sleeve 81 encloses the slotted pinion shaft 73 and that the rim or mouth of said sleeve is seated in the channel of said washer 83. 85 is a small rectangular plate or piece located across the inside of the handle-shaft-sleeve 81 with one end in the slot 73a of the pinion shaft. A helical spring 87 surrounds the handle-shaft-sleeve and has inwardly directed ends 87a projecting through the slot 81a in said sleeve far enough, when rotated 75

with the sleeve, to engage against the sides of the rectangular piece 85. A cylindrical casing 89 surrounds the entire assembly so that its inside wall is frictionally gripped by said helical spring 87 when it is in its relaxed and expanded state, but not when the coils of the spring are tightened up. This casing has a reduced neck 89a forming within it a bearing for the rotation of the handle-shaft 77. In the ordinary construction, this casing 89 is always non-rotary and is secured by its base to the stationary supporting plate 63. The operation of the aforesaid ordinary form of the device is as follows:—When the device is not being operated the helical spring 87 is relaxed and then frictionally grips the inside of the stationary casing 89 thereby causing the device, assisted by the other spring 79, to support the weight of the window in any given position. As soon as the handle 75 is rotated in either direction, the helical spring 87 is wound up more tightly by the advancing side of the slot 81a carrying with it the adjacent end 87a of the spring so that said spring no longer grips the inside of the stationary casing 89. After that, the same projecting end 87a of the spring, engaging the side of the rectangular plate 85, carries it around with the sleeve 81; and said plate, being located in the slot 73a of the pinion shaft causes said shaft and its pinion 71 to rotate to drive the toothed sector 59 to raise or lower the window depending on the direction of rotation of the pinion 71 and handle 75.

To the foregoing I add the following, besides strengthening the spring 79 as already stated:—Instead of securing the casing 89 non-rotatably to the fixed plate 63, I provide it with a flange 89b having radial notches 89c. Further I provide a lever 91 (Figs. 1, 2, 15 etc.) pivoted at 91a to the stationary plate 63 with a lateral projection or detent 91b on its lower end adapted to enter any one of the aforesaid radial notches 89c and thereby hold the aforesaid casing 89 releasably stationary. A spring 48 surrounds the pivot pin with its ends tensioned and fastened respectively to the fixed support 63 and the upper part of the detent lever 91 whereby said spring normally presses the detent into engagement with the notched rim 89b of the casing 89 thereby preventing it from rotating. An arch-shaped casing 93 (Figs. 16 and 17) is affixed by its base to the stationary plate. The neck 89a of the other casing 89 has its bearing in a hole 93a (Fig. 17) in the cross piece of the arch shaped casing. A tie-wire 50 (Figs. 1, 2, etc. 15) connects the upper end of the detent lever 91 with the slide 38 of the master-door dogging means; or in the case of the other doors connects with the lower end of a centrally pivoted lever 92 (Figs. 1 and 2) with its upper end engaging the rear end of the dog operating slide 86.

The operation of my aforesaid modifications of the usual device is as follows:—As long as the casing 89 is locked stationary by its detent lever 91 my device operates like the ordinary device, in that it permits raising and lowering of the window by hand; and the window will be frictionally held at the selected level by the frictional grip of the expanded helical spring 87. On the other hand, as soon as the doors are automatically locked from the locking of the master-door, the operation of the slides 38 and 86 of the dogging mechanism pulls on all the wires 50 and tilts all of the spring pressed detent levers 91 out of engagement with all of the casings 89 (Figs. 15 to 18) which then become free to rotate with the handle- and pinion-shafts and intermediate parts. Since

there is now nothing to prevent the rotation of the pinions 71 and toothed sectors 59, all of the springs 79 immediately assert themselves by rotating all of the sectors to close completely all of the windows.

Reversely as soon as the master-door is unlocked, all of the aforesaid slides 38 and 86 are restored to their normal position by the springs 48, and the pull on the wires 50 having been relaxed, the springs 48 again cause the detent levers 91 to engage the notched flange of the casings 89, so that the window operating devices again become individually operable from the handles 75.

A spring pressed pawl 95 continuously engages the notched flange 89b of each rotatable casing 89 preventing rotation of the casing and the other parts in window opening direction but not in closing direction. This last named feature prevents the closed windows from being forced down from the outside of the car.

Referring back to the description of the slide 38 on the master-door A, it might have been there stated that another function of said slide is of course to enable the master-door A to be unbolted at any time from within the car. Thus, by depressing the inside handle 43, Fig. 3, the lug 39a on the slide engaging the lug 12a on the bolt will cause the bolt to be retracted and permit the master-door to be opened.

Fig. 20 shows a modification wherein the master-door slide and its operating means are divorced from the outside door handle. In this figure, the spring-pressed bolt 12 is adapted to be retracted by turning the door handle shaft 16 and roll back 32 clockwise; but the shaft is lockable against such rotation by key operation of its slidable dog 20 to seat its lower end in the stationary socket 97 on the plate 10 of the lock. The slide 38 is retractable by the spring-tensioned wire 50 like the corresponding slide in Fig. 1; and reversely may be pushed forward by the cam 101 on the shaft 103 rotatable by the handle 105 on the inside of the master-door. Spring detent 107 releasably engages notches on the cam at its active and inactive positions.

Assuming the devices in Fig. 20 to be substituted for the corresponding devices on the master-door in Fig. 1, it will be understood that by operating the handle 105, the high part of the cam can be made to force the slide 38 into its outermost position. Ordinarily this will be done when the master-door is open. If so, upon closing said door, the projecting end of the aforesaid slide 38 entering the related slot in the post E (compare Figs. 9 and 10) will force the adjacent tablet 98 inwardly and, through the intermediate devices, will operate the other tablets 98 as heretofore described to operate the slides 86 of the other doors to dog their bolts. Similarly this will result in closing the windows of said doors. Finally the master-door itself may be locked by turning the key to seat the dog 20 (Fig. 20) in the socket 97.

Fig. 21 shows another modification which, like the modification in Fig. 20, is substitutable on the master-door in Fig. 1. As heretofore, the same or analogous parts have been given the same numerals to economize description. The novel part in Fig. 21 is the cam-lever 109 pivoted at 111 to the plate 10. When the dog 20 is key-operated into its up position as shown in this Fig. 21, it bears against the upper end of the cam lever, so that the lower end of the lever (contained within the forked rear-end of the slide 38) pushes the slide into its outermost posi-

tion. The cam lever 109 in this position simultaneously dogs the roll-back 32 so that it cannot be rotated clockwise to retract the spring-pressed bolt 12 due to the fact that the abutment 109a of the cam-lever is then interposed between the side of the dog 20 and the pivot 111 of the lever.

Ordinarily the described position of the parts as in Fig. 21 will be accomplished by turning 10 the key in the master-door while open. Then upon closing the door, the spring-pressed bolt 12, after riding to the right against its spring, will then spring outwardly into its socket in the adjacent post, whence it cannot be retracted by 15 turning the door handle except by using the key to lower the dog 20. Also the slide 38, as the door closes, will pass into the slot 96 (compare Figs. 9 and 10) and push inwardly the related tablet 98 and through same and the other devices, as already explained, will automatically dog the bolt retracting means of the other doors.

It will be noted that the form of the invention shown in Fig. 21 differs in that the master-door slide 38 is operated into its dogging position by 20 the key that operates the dog 20, instead of as in the other forms by the turning of the master-door handle and its shaft 16, or by turning the cam in Fig. 20.

Fig. 22 shows another modified construction 30 for use in connection with the doors A and B and the post E as a substitute for the construction shown in Fig. 1. The same or analogous parts in the two figures have been designated by the same numerals so as to save description. 35 The construction in Fig. 22 also compares with that in Fig. 20; and the same or analogous parts in common have been designated by the same numerals. The difference between the constructions in Figs. 20 and 22 is that in Fig. 22, 40 the cam 101 has been removed from the master-door to within the center post E, where it acts directly on the slide 86 of the door B through the intervening swinging tablet 98. The handle is of course on the inside of the car on the free 45 end of the cam shaft 103 which projects through the wall of the center post E. The Bowden-wire 50 35 operatively connects the cam 101 to the tilting cam-lever 37 in the center post F on the opposite side of the car to operate the tablets 98 and the dogging slides 86 on that side of the car, as already described in connection with the construction shown in Figs. 1 and 2.

Thus the construction in Fig. 22 used in connection with the construction in Fig. 2 enables 55 the simultaneous locking of the non-master doors B, C, and D and the automatic closing of their windows from the single control 105 within the car. As to the master-door, this is locked by using the key to seat the dog 20 in the stationary socket 97, thereby preventing the operation 60 of the roll-back 32 to retract the bolt 12.

It will be understood that the expression "locking means" herein includes any means for dogging the bolt retracting means and may or may 65 not include key-controlled or key-actuated means.

What I claim is:

1. In combination with an automobile body, a master-door; means for locking same from the 70 outside of the car; other doors, bolt means for said other doors; retracting means for each bolt means; dogging means for each of the retracting means, including a movable part at the edge of each door whereby its dogging means is operable; 75 a single controller inside the car for a plurality

of said dogging means; and mechanical means operative between said controller and the aforesaid parts whereby said parts are simultaneously operable from said controller.

2. The combination with an automobile body 5 and its doors, of posts at the edges of said doors apertured adjacent said edges; tablets operatively supported by said posts at said apertures; means comprising devices carried by said posts between said tablets whereby operating one tablet 10 operates other tablets; a controller arranged to operate one tablet and through it to operate other tablets; and locking means on said doors comprising movable parts located at said tablets and operated by movement thereof. 15

3. In combination with an automobile body, bolt means for the master-door, means for retracting said bolt means and means for dogging said retracting means comprising a movable member at the vertical free edge of said door, 20 another door; bolt means for same; and dogging means for same associated with and responsive to the aforesaid movable member whereby the dogging motion of said member operates said dogging means of said other door. 25

4. In apparatus of the character described, the combination of a master-door; outside handle operated bolt-means for said door; means for dogging said bolt means, likewise operated by said handle, comprising a movable member at 30 the vertical free edge of the door; another door; outside-handle operated bolt means for said other door, and means for dogging said last named bolt means associated with the dogging means of the master-door and operated by the aforesaid member thereof. 35

5. The combination with an automobile vehicle body provided with a plurality of doors and a latch on each door normally maintaining the same in closed position, means for retracting 40 each latch including an outside handle, means associated with each latch adapted to lock its said retracting means against operative movement; and mechanical means adapted to cause the operative movement of said locking means, 45 holding said retractive means of one door against operation, to lock said retractive means of other doors against operation; said last named means including a movable element in each, adjacent an aperture in the free vertical edge thereof. 50

6. In combination with an automobile body, a master-door, bolt means for said master-door, bolt retracting means on said master-door, and means for dogging said bolt retracting means including a movable member in a vertical edge 55 of said door, a remote door, a post at a vertical edge of said remote door, bolt means for said remote door, bolt retracting means on said remote door, and means for dogging said remote door bolt retracting means including a movable part 60 in the vertical edge thereof adjacent said post whereby said dogging means on said remote door is operable, and mechanical means including devices within said post accessible to and operative between the aforesaid master-door member and the aforesaid parts whereby the bolt dogging motion of said member operates said parts to dog the bolt retracting means on said remote door. 65

7. In combination with an automobile body, a 70 master-door, bolt means for said master-door, bolt retracting means on said master-door, and means for dogging said master-door bolt retracting means including a movable member in the vertical free edge of said door, a remote door. 75

a post at the vertical free edges of said doors, bolt means for said remote door, bolt retracting means on said remote door, and means for dogging said remote door bolt retracting means including a movable part in the vertical free edge of said remote door whereby its dogging means is operable, said post being horizontally slotted to receive and pass freely the aforesaid member and parts, and mechanical means including devices within said post accessible through said slots and operative between the aforesaid master-door member and the aforesaid remote door parts whereby the bolt dogging motion of said master-door member operates the remote door parts to dog said remote door bolt retracting means.

8. The combination with an automobile body, a non-master-door, a bolt on said door, means on said door to retract said bolt, a handle mounted on the outside of said door adapted to operate said retracting means, a dog on said non-master-door engageable with the bolt retracting means on said door, a part movably mounted in the vertical free edge of said non-master-door for operating said non-master-door dog, a master-door, a bolt on said master-door, means to retract said master-door bolt, means for dogging said master-door bolt retracting means and at the same time operating the aforesaid part of the non-master-door into its dogging position, and an inside handle on the non-master-door operative to retract its bolt and at the same time disengage the dog and associated bolt retracting means on said non-master-door.

9. The combination with an automobile body provided with a plurality of doors, means for simultaneously locking said doors against unauthorized ingress, and means associated with each of said doors effective when the same is opened from within and closed to maintain the same unlocked until the several doors are again simultaneously locked.

10. The combination with an automobile body provided with a plurality of doors, swingable into and out of engagement with adjacent fixed body units, coincidental locking means for said doors, including a movable member projecting from one of said doors at an edge thereof and a cooperating movable part on the body adjacent said projecting part, and the fixed body structure adjacent said cooperating movable part provided with an opening whereby said projecting part may swing into engagement with its said cooperating movable part as said door is moved into closed position.

11. A mechanism for securing a pair of doors mounted to have their free edges abutting an interposed stile post, comprising a lock upon each door and including a reciprocable bolt and an operator therefor, latching means in each lock oscillatable to secure the adjacent operator against movement, reciprocable elements disposed between the door locks, and adapted when shifted in one direction to oscillate said latches to bolt operator securing position, and means for simultaneously shifting said elements.

12. Securing mechanism for a pair of remotely related door members, comprising a lock carried by each door, a bolt carried by each lock for engaging an adjacent keeper, means for actuating the bolt of each lock, a latching element in each lock oscillatable to secure the actuating element against movement, means mounted upon a fixed structure adjacent each door lock for oscillating said latch, and means connecting said last men-

tioned means for effecting the simultaneous actuation thereof.

13. In an automobile having a door, means operable from a station remote from said door for locking it against unauthorized ingress, and means effective when said door is opened from within, while locked from said remote station, to maintain said door in unlocked condition when again closed.

14. In combination with a vehicle body having doors on opposite sides, means for holding each door closed and means inside and outside each door for releasing said holding means, and means responsive to movement of said inside releasing means of a door on one side of said body to render the outside releasing means of a door on the opposite side of said body ineffective to release its holding means.

15. In combination with a vehicle having a plurality of doors, a lock for one of said doors including means for holding said door closed and means for releasing said holding means; a locking system for said doors including a pin projecting from said lock for rendering said releasing means ineffective, and an operator with which said pin is operably associated whereby operation of said operator will operate said pin to thereby render said releasing means ineffective to release said holding means.

16. The combination with a vehicle having a plurality of doors, each door having means for holding it closed and means to release said holding means, a coincidental locking system including a train of movable parts extending between said doors for rendering said release means ineffective to release said holding means, means on the interior of said vehicle for operating said system to lock said doors, and means on the exterior of said vehicle to unlock said doors when locked by said interior means.

17. In a locking means for a pair of doors disposed side by side, a post between said doors, a pin extending from each door toward said post, movable parts in said post adapted to abut said pins, locking means for one door adapted to project one of said pins, locking means for the other door operable by movement of its associated pin toward said other door, and means for actuating the locking means for said one door to transmit motion to said post parts and to the pin on said other door to consequently lock both doors.

18. In a locking means for a pair of doors disposed side by side, a post between said doors, a pin extending from each door toward said post, movable parts in said post operably associated with said pins, locking means for one of said doors including its associated pin, and control means for effecting the operation of the other of said pins to transmit motion to said post parts and to the pin on said one door to lock the latter.

19. In combination with a vehicle having a plurality of doors, each door having means for holding it closed and release means for said holding means, a coincidental locking system for rendering said release means ineffective to release their associated holding means and including a train of movable parts from one door to another, and means on the inside of one of said doors for operating said locking system.

20. In combination with a vehicle having a door, said door having a lock including means for holding the door closed and release means for said holding means, a locking system for rendering said release means ineffective to release

its associated holding means and including a train of movable parts extending from said lock to a point on the inside of said vehicle remote from said door and there provided with an actuator 5 for operating said locking system.

21. In combination with a vehicle having a plurality of doors, said doors having means for holding them closed and means for releasing said holding means, a coincidental locking system 10 including a train of movable parts operatively connected with said releasing means and a controller for rendering the said releasing means on all but one door ineffective to release the associated holding means.

15 22. The combination with a vehicle having at least two doors and at least one of said doors being provided with a latch bolt, an inside latch bolt actuating handle on one of said doors, and means responsive to movement of said handle 20 for locking the other door against unauthorized ingress.

23. In combination with a vehicle body having a hinged door, means for holding said door closed, means for releasing said holding means, means 25 for rendering said releasing means ineffective for releasing said holding means, operating means for said last named means including a part extending to one of the free edges of said door and a part in said body adapted to actuate said first 30 named part, and operating means for said second named part including a train of operatively connected movable parts extending to a point on said body remote from said door.

24. In a vehicle body, a plurality of hinged 35 doors, locking means for one of said doors including a train of operatively connected movable parts extending to another door and including a slide member on said other door adapted to project from the free edge thereof when in locking 40 position, and means for locking said slide member in projecting position.

25. In a vehicle body having a plurality of doors with at least one door on each side of said body, locking means for all of said doors, inter- 45 connecting means between said locking means whereby all of said doors may be locked or unlocked simultaneously, latch bolt means for each of said doors, inside latch bolt controls for each of said doors, interconnecting means between said 50 locking means and one of said inside latch bolt controls whereby said last mentioned inside latch bolt control actuates all of the locking means to thereby lock all of said vehicle doors.

26. In a vehicle having a front door, a rear 55 door, and a post intermediate said doors, the combination with locking mechanism carried by said rear door and cooperating with said post to retain said rear door in closed position, of means carried by said post and associated with said 60 locking mechanism for causing release of the latter, and manually operable means carried by said front door and connected with said means for actuating the latter to lock said rear door.

27. An automobile body having hinged doors 65 on opposite sides thereof, each door having its free edge abutting a body post, each door having a latch bolt for engagement with the post and an outside handle and a handle operated bolt actu-

ating member, a key operated lock in the handle of one door, a slide member carried by said one door and actuated by the handle thereof, said slide member having a portion protruding beyond the free edge of the door, a pin adjacent the free edge of a door on the side opposite said one door, locking means carried by said last named door and operable by its associated pin, and said pin having an operative connection with said protruding portion of said slide member whereby it is shifted by movement of the latter. 5

28. The combination in an automobile body of a door at each side set in a frame of the body, each door being hinged at one edge to the frame and having a free edge engaging a post of the 15 frame, each door having an outside actuator and door holding means operable thereby, a shiftable member in each post, said shiftable members being interconnected by a train of movable parts to move together, means for actuating a locking 20 member carried by each door for precluding release of the door holding means by its actuator, each locking member actuating means extending to the free edge of its door and having cooperating motion-transmitting engagement with an associated shiftable member whereby shifting of the latter actuates the locking member actuating means, and means for shifting said shiftable members for effecting the locking of the doors 25 through the locking member actuating means. 30

29. The combination in an automobile body of a door at each side set in a frame of the body, each door being hinged at one edge to the frame and having a free edge engaging a post of the 35 frame, each door having an outside actuator and door holding means operable thereby, a shiftable member in each post, said shiftable members being interconnected by a train of movable parts to move together, means for actuating a locking 40 member carried by each door for precluding release of the door holding means by its outside actuator, each locking member actuating means extending to the free edge of its door and having 45 cooperating motion-transmitting engagement with an associated shiftable member whereby shifting of the latter actuates the locking member actuating means, and key controlled lock means for shifting said shiftable members for effecting the locking of the doors through the locking member actuating means. 50

30. In a motor vehicle, door securing mechanism for doors upon two sides of the vehicle comprising a lock for each door including a bolt designed to engage a keeper to secure the door in closed position, means for actuating the bolt of each lock, a latching element in each lock adapted to be shifted to secure said bolt actuating means against movement, a reciprocable element mounted upon a fixed portion of the vehicle body adjacent each lock and arranged to engage the adjacent latching element when shifted in one direction, means adjacent each reciprocable element for effecting its reciprocation, a connection between said last means for causing the simultaneous operation thereof, and means for operating the reciprocable element actuating means. 55

EDWARD D. DALL.

CERTIFICATE OF CORRECTION.

Patent No. 2,102,997.

December 21, 1937.

EDWARD D. DALL.

It is hereby certified that error appears in the printed specification of the above numbered patent requiring correction as follows: Page 4, first column, lines 66 and 67, strike out the words and period "When a door re-opened from the outside."; line 67, after "is" insert opened, under such circumstances, slide 86 moves; page 6, second column, line 21, claim 3, before "and" insert retracting means for said last named bolt means; line 22, same claim, for "same" read said retracting means; and that the said Letters Patent should be read with these corrections therein that the same may conform to the record of the case in the Patent Office.

Signed and sealed this 8th day of February, A. D. 1938.

Henry Van Arsdale,

(Seal)

Acting Commissioner of Patents.
